UNITED STATES PATENT OFFICE

ULRICH BISCHOF, OF AARAU, SWITZERLAND

MACHINE FOR KNOTTING WARPS

Application filed May 29, 1929, Serial No. 367,024, and in Switzerland October 4, 1928.

Machines are already known for tying the ends of warp threads, wherein the warp threads of the old warp and of the new warp are horizontally clamped in the machine. 5 These machines however have the disadvantage that the device for clamping the warp and the knotting device are arranged wholly or partly above the warp, and thereby render impossible the free and unhampered accessibility of the plane of the warp for quick clamping of the warp and a continuous, constant and complete supervision for controlling purposes during the tying. 10 In other known machines the old and new warps are clamped in a vertical position, but these machines have the disadvantage that the knotting device is arranged above the warp and engages with the latter for tying purposes on both sides, thereby preventing satisfactory oversight of the warp during the tying, so that the tying of the correct associated threads cannot possibly be controlled at the right time. Faults that are discovered too late may however occasion 15 great losses of time. Moreover the clamping of the old and new warps is in such machines very complicated, since the gripping bars supported by rotatably arranged locked carrying arms have to be unlocked before the 20 clamping of the warp, rocked downwards, and brought back into the upright position after the clamping and locked again.

This arrangement is also known in the case of double machines coupled together. 25 With this arrangement, however, an uninterrupted automatic transport of the knotting device and a successive tying of the warp clamped in a plurality of coupled machines, is precluded. With these machines the knotting device must be transferred from one machine to the other by hand, and this involves a preliminary partial dismounting of the knotting apparatus, which has to be re-assembled after being transferred, thereby occasioning a good deal of work and loss of 30 time.

With the machine forming the subject-matter of the present invention, the said disadvantage of the machines hitherto known 35 are obviated owing to the fact that the de-

vice for clamping the old and new warps and the device for tying the ends of the threads are so arranged that ready accessibility, which is necessary for the quick clamping of the warp, is obtained owing to a free and unhampered warp plane, which renders possible a continuous, constant and complete oversight for controlling purposes of the tying of the warp and of the warp threads already knotted, in such a way that in one 60 working operation and without interruption all the threads of warps of any desired breadth can be tied, the knotting device, after the knotting thereof has been effected, being capable of being transferred by an uninterrupted automatic transporting means to a second machine coupled to the first, for the purpose of tying warp threads clamped on the second machine, during which time 65 fresh warps can be clamped on the first machine for tying purposes, thereby increasing the output of the machine. 70

According to the present invention this machine is distinguished by the fact that the clamps that receive the fresh warp are carried by carrying members provided with running rollers arranged underneath the warp planes, and form, together with the latter, a travelling warp carriage, that parts of these carrying members extend underneath a driving shaft arranged in the longitudinal direction between the clamps and having a driving connection with a knotting device, that this shaft and the knotting device are arranged inside the travelling warp carriage, 75 that the driving of all the knotting implements is effected from below, and that the warp carriage travelling on rails, is automatically displaceable without hindrance in the longitudinal direction by a machine provided with a mounted warp, towards one or more machines coupled with the former, for the tying of the previously prepared and clamped warps, the whole in such a way that a quick and easy clamping of the warps and 80 a complete and continuous supervision of the warp during the clamping, as well as during the tying thereof, is obtained, over the entire longitudinal front even with a plurality of machines coupled together. 85

Preferably also the running rails of the knotting carriage, as well as the two toothed racks, which are provided for the purpose of displacing the knotting device, with its carriage, relatively to the warp, and for the purpose of compensating one warp relatively to the other by displacement of the warp carriage, are arranged inside the warp carriage, the transverse connection of the bows being 5 preferably likewise constructed continuously underneath the running rails and racks, in such a way that the carriage, with the knotting device, can advance uninterruptedly and automatically from one machine to the other 10 in the entire longitudinal direction for the purpose of successively tying the warp clamped upon each machine.

The rollers of the warp carriage are preferably arranged directly on the bow thereof, these rollers being arranged upon stay rods, likewise preferably directly, which connect the side frames of the machine together, whereby a simplification of the machine is obtained.

25 One constructional example of the invention is illustrated in the accompanying drawings, wherein

Figure 1 shows the machine in side elevation, with some parts in section, and

30 Figure 2 shows the machine in front elevation, a second machine being partly shown.

Figure 3 is a side elevation of the warp carriage, with the knotting device, some parts being in section on the line $\alpha-\alpha$ in Fig. 2,

35 Figure 4 is a front elevation of the warp carriage,

Figure 5 shows the knotting device, with the driving shaft, in front elevation,

Figure 6 shows a part of the warp carriage.

40 Figure 7 is a front elevation of the keys, warp stop motion and the coupling and ratchet lever mechanism associated therewith.

Figure 8 is a plan of the keys, warp stop motion and the coupling and ratchet lever mechanism associated therewith.

Figure 9 is a side elevation of the thread-removing means.

45 Figure 10 is a front elevation of the thread-removing means.

Figure 20 is a front elevation thereof.

Figure 21 is a front elevation of the bush 70 with toothed wheel and the lower part of the binding bill also a plan thereof and a side elevation and plan of the upper part of the binding bill.

Figure 22 is a front and side elevation of 75 the needle.

In Figures 1 and 2, 1 denotes the side frames of the machine, which are stayed by connecting rods 2, 3, 4 and 5. To the side frames are secured running rails 6 and 7, upon which are mounted rollers 9 and 10 rotatably arranged on a knotting carriage 8 to facilitate the displacement thereof. The driving shaft 11 is journalled in bearings 12 secured to the side frames and carries at one end a driving pulley 13. The shaft 11 carries a toothed wheel 14 (Fig. 5), which meshes with a second toothed wheel 15, of which the shaft 16, arranged on the knotting carriage 8, carries the pulleys with the cam discs, not shown, designed for actuating the knotting implements. The driving shaft 11 has a groove 17 (Fig. 3), in which there engages a key 18 (Fig. 1) of a clutch 19 (Fig. 5) arranged beside the wheel 14. On the knotting carriage is arranged a shaft 20 (Figs. 1 and 5), upon which is rockably mounted a two-armed lever 21, one arm of which engages with the jaws 22 in a groove 23 in the clutch 19, and the other arm of which is constructed in two parts. The part 24 is slidably and clampably arranged on the other part of the lever 21 by means of a slot and a screw 25 (Fig. 1), the part 24 being brought into the lowest position for the purpose of pushing the knotting carriage backwards under the previously mounted fresh warp of the first machine by hand, when the knotting carriage is to be brought into its lateral initial position. The part 24 is pivotally connected with a feeler 27 guided in a support 26. The double arm 21 is also connected with a braking arm 28 (Fig. 1), the roller 29 of which is drawn against a cam disc 30 by a spring 31.

On one end of the shaft 20 is rotatably arranged a toothed wheel 33 (Fig. 1) meshing with a rack 32 secured to the side frames, while upon the opposite side of the shaft 20 is provided a toothed wheel 36 meshing with a rack 35 secured to downwardly bent bows 34 (Figs. 1, 2 and 3). Bearing upon these wheels there are mounted loose upon the shaft 20 ratchet levers 37 and 38, of which the pawls 39 and 40 each engage in a second set of teeth on the toothed wheels 33 and 36. The rollers 41 and 42 of the ratchet levers 37 and 38 are pressed by springs 43 and 44 on the same cam, not shown, of the disc 45. In the support 26 (Figs. 1, 7 and 8) is journalled a shaft 46, on one end of which is fix- 110 115 120 125 130

edly mounted a lever 47, which is pivotally connected by a tension rod 48 with the ratchet lever 38, while upon the other side of the shaft 46 is secured a lever 49. Beside this lever is rockably mounted upon the shaft 46 a lever 50, which is likewise pivotally connected by a tension rod 51 with the ratchet lever 37. Keys 52 and 53 (Figs. 1, 7 and 8) are rockably arranged in a support 54 and 10 constructed with projections 55 and 56, and one end of each of the levers 49 and 50 comes to lie under these projections. The keys 52 and 53 bear on the warp threads and assume during the tying of the threads a variable 15 position, in such a way that the projections 55 and 56 of the keys stand at times in front of the ends of the levers 49 and 50, and these levers are therefore no longer obstructed in their freedom of movement, and the ratchet 20 mechanisms connected with them come into operation, on the one hand for the purpose of displacing the knotting carriage relatively to the warp and on the other hand for the purpose of displacing the warp carriage in order to equalize the correct position of the 25 two warps one above the other. Under these circumstances the keys 52 and 53 bearing upon the threads, owing to this displacement of the knotting carriage, return to the initial 30 position, and the operativeness of the ratchet mechanisms and of the levers 49 and 50 is thereby also interrupted again, and this is constantly repeated in an alternating manner.

35 The grips 57 and 58 (Figs. 1 and 3), known in themselves, are carried by the downwardly bent bows 34, the latter being connected with one another by a rod 59, and forming together with rollers 60 rotatably arranged upon the pivot 61 secured in the bows, a travelling warp carriage. The grip 57 is movably arranged in a known manner, being carried by a shaft 62 journalled in the bows 34 and a support 63 fixedly mounted upon it, a crank 40 64 (Figs. 3 and 4) bearing on each side against a stop on each support 63. Underneath the grip 58 is provided a rod 65 (Figs. 1 and 3) as a connecting member for the bows 34. The grip 66 (Figs. 1 to 3) bears upon the two supports 67, which are provided with racks 68, and which are displaceably supported in supports 69 secured to the side frames 1 of the machine and are secured by screws 70. In the side frames 1 is journalled a shaft 71 (Figs. 1 and 2), upon which is fixedly mounted a hand lever 72, while a shaft 73 is immovably carried by levers 74 mounted fast on the shaft 71. Further levers 75 located upon the shaft 73 are two-armed levers and are arranged slidably upon the shaft 73, in such a way that downwardly directed arms of these levers engage over the shaft 71, whereby these levers are guided. The upper arms of the levers 75 carry the beam 76, with the fresh warp 76¹. On the

side frames 1 (Figs. 1 and 2) are secured supports 77 carrying the beam 78 with the old warp 78¹, the harness 79 provided with the old warp being suspended from holders 80. Upon a bar 81 secured to the supports 77 two 70 holder guides 82 are longitudinally displaceable, in which the holders 80 are so arranged as to be adjustable in height by means of a screw 83 in each case. Above a cylinder 84, which is rotatably and removably arranged in the supports 77, the old warp carried by the harness and gripped in a known manner in the space 78 is guided forward for tying.

A tube holder 85 (Figs. 5, 9, 10 and 11) with pin 86 and cams 87, is inserted into the bore of a boss 88 (Figs. 1, 3 and 5), the cams 87 engaging in a slot in this boss 88, and thereby giving the correct position to the tube holder 85. In the tube holder are rotatably arranged tubes 89, 90, 91 and 92, in the bores of which so-called cords or lease bands 93 (Fig. 11) are drawn through in a known manner, the warps lying crosswise above the latter, and the threads being taken away individually. Upon the tubes are secured levers 94, 95, 96 and 97, and pins 98, 99, 100 and 101 rotatably arranged therein engage in a common disc 102 rotatably arranged upon the holder 85, and set longitudinal ribs 103 constructed on the tubes for oscillation 95 during a rotation of the said disc. For the rotating of this disc 102 there engages in a slot therein a pin 104 (Figs. 3 and 5) on a lever 106 arranged on the knotting carriage 8 and rotatable upon a pin 105, while a roller 107 arranged on the other end of the lever 106 engages in a cam groove, not shown, in a disc 108, and, during the rotation of this disc, sets in oscillation the longitudinal ribs 103 formed on the tubes. The disc 108 is 100 constructed with a toothed wheel 109 and is rotatably supported upon a pivot 110, the toothed wheel meshing with a toothed wheel 111 mounted fast upon the shaft 16. On the tube holder is arranged a thread divider 105 112 (Figs. 3, 5, 10 and 11) upon a rotatable and longitudinally slideable shaft 113, a tappet 114 (Fig. 5) being mounted fast on the other end of the shaft 113. A lever 115 rotatably arranged on the knotting carriage 8 110 upon a pin 116 engages with a prism 117 mounted loose upon a pin 118 in a slot in the tappet 114, and carries at the other end a roller 119, which bears upon a disc 120 fixedly 115 connected with the toothed wheel 109, so that during the rotation of this disc, owing to a cam groove, not shown, arranged thereon, a longitudinal displacement of the thread divider is effected. A lever 122 (Figs. 3 and 5) rockably arranged on the knotting carriage 8 upon a pin 121, is forked at one end, a pin 123 provided on the tappet 114 engaging in the slot between the prongs of the fork. The other end of this lever 122 is provided with a roller 124, which bears on a cam groove, 120 125

123 124 125

not shown, in the disc 120. During the rotation of this disc the thread divider is set in oscillation. On the knotting carriage 8 a rod 125, with a shear cutting plate 126 (Figs. 15 and 16), is vertically displaceable, the said rod being provided at the other end with a tappet 127 mounted fast thereon and with a pin 128 and a pivoted tension rod 129. The latter is pivotally connected with a lever 131 rockably arranged upon a shaft 130 and with a pivot 132. The lever 131 has a roller 133, which engages in a cam groove, not shown, in a disc 134, the knife plate 126 being moved up and down during a revolution of the said disc. In the bore of the rod 125 a rod 135 provided with a knife plate 136 is similarly arranged in a vertically displaceable manner, a tappet 137 being mounted fast on the other end of the rod 135 and being pivotally connected by a pivot 138 with a tension rod 139. Upon the shaft 130, which is fixedly arranged on the knotting carriage, is mounted a rockable lever 140 provided with a roller 141, which engages in a cam groove, not shown, in the disc 134, and, during one revolution of the latter, the lever 140, pivotally connected with the tension rod 139 by the pivot 142, likewise moves the knife plate 136 up and down in such a way that during the displacement of the two knife plates 126 and 136 the threads are cut off as if with shears.

A support 143 secured to the knotting carriage 8 carries a two-armed lever 145 rockably mounted upon a pivot 144, one arm of the said lever carrying a lever 147, which is likewise rockably arranged upon a pivot 146 (as shown in Figs. 3, 5, 17 and 18). The lever 147 is provided with a tubular hook needle 148, which is secured in the lever 147, and in the bore of which a rod 149, provided with a positioning ring 150 and subject to the pressure of a spring 151, is longitudinally slidable. The hook needle 148 forms, with the rod 149, a thread grip. The lever 147, with the roller 148', and the lever 145, with the roller 148'', are connected with one another by a spring 152, whereby these rollers are pulled against the cam grooves, not shown, in discs 153 and 170. A lever 155 rockably mounted upon a pin 154 on the lever 147 (Figs. 3 and 17) engages with a roller 156 in a cam groove not shown, in a disc 153, and the hook needle 148, during one revolution of the disc 153, executes a vertical and oscillating movement, the rod 149 likewise executing a reciprocating movement in the tubular hook needle, for the purpose of seizing and clamping the thread and supplying it to the binding bill.

On the knotting carriage is rotatably arranged a binding bill 157 (Figs. 3, 19, 20 and 21), which is mounted fast upon a bush 159, provided with teeth 158, in the bore of which is arranged a longitudinal rod, with the binding bill 157'. The other end of this rod

carries a ring 160, and a spring 161 presses the binding bill jaws 157 and 157' against one another. A bush 162 is longitudinally slidable upon the fixed ring 160, a second spring 163 pressing a shoulder of this bush against a shoulder on the ring 160, and thereby pressing the jaws of the binding bill firmly against one another. The rotating of the binding bill is effected by a rack 164 (Figs. 19 and 20), which is arranged on the knotting carriage and which is guided in bearings 165 and 166, and is provided with a pin 167 (Fig. 3) with a prism 168. The latter engages in the fork of a two-armed lever 169, which is rockably arranged upon the pivot 130, and engages with a roller 133' in a cam groove, not shown, in a disc 170. A lever 171, (Fig. 3) rockably arranged upon the pivot 144, bears by means of a roller 172 upon the cam groove of the disc 153, so that during one revolution of the discs 170 and 153 the rotation of the binding bill and the opening and closing thereof are effected by the displacement of the binding bill rod, for the purpose of executing the tying of the threads.

A hook needle 172' (Figs. 3, 12 and 22) is mounted in a holder 173, which is secured to a pivot 174 and oscillatably arranged on the knotting carriage, a two-armed lever 175 being rockably mounted upon the boss of the knotting carriage, and one arm of this lever serving as a tappet for the needle 172. The other arm of the lever 175 is pivotally connected by a pivot 176 with the tension rod 177, (shown in Figs. 3, 5 and 12). A pivot 178 connects the rod 177 with a lever 179 mounted upon a pivot 180 on the knotting carriage, the roller 181 of which bears upon a cam groove, not shown, in a disc 182, and during the rotation thereof sets the hook needle 172 in oscillation.

Upon the knotting carriage is secured a support 183 (Figs. 3, 5 and 12), in which is journaled a shaft 184 carrying a lever 185. The lever 185 engages between a ring 186 mounted fast upon the shaft 174 and the holder 173, there being mounted fast upon the other side of the shaft 184 a lever 187, of which the pin 188 engages with a prism 189 in a slot in a lever 190. The latter is oscillatably arranged upon the shaft 130 and engages, with a roller 191, in a cam groove, not shown, in a disc 192, which, during its rotation, imparts to the hook needle 172, besides the oscillating movement previously mentioned, an up and down movement, for the purpose of gripping the thread, then supplying it to the binding bill, pulling the knotted threads out of reach of the knotting implements and giving them up.

To the knotting carriage is secured a support 193 (Fig. 5), in which is journaled a shaft 194, carrying a toothed wheel 195. The wheel 195 meshes with a toothed wheel 196, rotatably arranged upon the tube holder 85,

70

an angle 197 secured to the tube holder engaging in a groove in the wheel 196 and thereby holding the latter fast axially (Figs. 3, 5, 9, 10 and 11). Upon the other side of the shaft 194 is secured a chain wheel 198, which is connected by a chain 199 with a second chain wheel 200 (Fig. 5) mounted fast upon the boss of the disc 192. During one revolution of the wheel 200, a hook 600 (Fig. 10) secured to the toothed wheel 196 executes an oscillating movement and thereby draws away the cut thread ends lying upon the tubes 89, 90, 91 and 92. A stop motion 201 (Figs. 9 and 10) engaging in the warps 76' and 78' is rotatably arranged on the tube holder 85 upon a pin 202, and this stop motion, when one thread misses, is pulled from the other of the two threads to be tied on to one side or the other, that is downwards or upwards, and thereby renders possible the displacement of the feeler 27 and automatically puts the knotting implements out of operation.

The method of working of the machine described is as follows:—

The fresh warp 76' located upon the warp beam 76 is pulled in an upward direction and is clamped and gripped at the rear and front grips 57 and 58, known in themselves, the second grip 57 from the front being rotatably mounted upon the shaft 62 and the clamped warp 76 being capable of being brought to the desired tension by rotating one of the cranks 64 arranged on both sides of the grip 57. Thereupon the front grip 66, which has been brought into the lowest position for an unhampered clamping of the previously described warp 76 by rotating a crank 640 (Fig. 2), is raised into the uppermost normal position and locked with the screw 70. One end of the old warp 78' is clamped and gripped in a known manner to the rear clamping beam 78 rotatably arranged on the machine, while the other end of this warp is slid forward over the rotatably arranged roller 84 and clamped and gripped in the front grip 65, this warp lying at a slight distance above the former and being capable of being placed under tension in case of need by rotating the clamping beam 78, which is provided with a ratchet wheel 641, and a ratchet lever 642 shown in Fig. 2. The clamping of the two warps is thus effected in a horizontal position one above the other, an easy clamping and gripping of the warps in the grips 57, 58 and 66 being obtained from the front of the machine in consequence of the absence of all projecting and obstructing parts above the warp, and a readily accessible and convenient clamping and gripping of the warps in the clamp being obtained from the front of the machine, besides a complete supervision over the warp. After the clamping of the warps, the knotting carriage 8 is pushed into the initial position on the right (Fig. 2), as seen from the front of the machine, against the warps 76' and 78', the known cords 93 located in the warps being pulled in a known manner through the bores of the engaging tubes 89 to 92 of the knotting device and being fastened outside the machine. The knotting device is thereupon set in operation, the threads of the old and new warps to be tied being taken away one after the other by special means mentioned in my co-pending application No. 367,026, filed May 29, 1929 (Case C), and these threads being seized by the knotting implements, whereupon a linking and knotting is effected in the manner described in my specification No. 367,025 filed May 29, 1929 (Case B), and the tied threads or subsequently laid down in succession.

If the clamped warps in a plurality of machines coupled together are to be tied in succession in the same direction of feed, the knotting carriage may be very easily brought back again by hand, with the knotting device, into the initial position after the first machine, the knotting implements being previously brought into the lowest position by rotating the driving wheel by hand, as well as the lever 24, by loosening the fastening screw 25, the feeler 27 being thrown over, and thereby assuming a downwardly hanging position for the purpose of pushing through the knitting carriage, after the removal of the tube holder 85 mounted thereon, and reversal of two pawls 39 and 40, underneath a previously reclamped warp, the tooth wheel provided on the driving shaft with a key engaging in the longitudinal groove in the latter being shifted, together with the knotting carriage, so that the actuation of the knotting implements can be effected from the same driving shaft over the entire longitudinal direction of a plurality of machines coupled together.

It will be clear from the foregoing that from the special construction and arrangement of the warp carriage, the bridge pieces of the bows 34 passing through underneath the driving shaft, the knotting device, the running rails for the knotting carriage and the racks for the displacement of the warp carriage and the knotting carriage being arranged within the travelling knotting carriage, an unhindered automatic displacement of the knotting carriage, with the knotting device, is obtained without interruption from one machine to a second machine, and so forth, and a continuous tying of the warps clamped on a plurality of machines coupled together is effected. Under these circumstances a continuous clamping of the warps by the workers in charge of the machine, simultaneously with the tying of the previously clamped warps, is rendered possible, and therefore an exceedingly high output is obtained from the machine.

By the special construction and simple arrangement of the warp carriage and knot-

ting carriage in conjunction with the driving shaft and the sliding and displacing members, together with the special arrangement of the driving members for actuating the implements for displacing the knotting and warp carriages, as well as those for the automatic throwing of the knotting carriage out of action, as well as the implements for taking away the threads from the warp, and those for linking and tying the threads, there is obtained underneath the latter and the warp a free and readily accessible warp plane, which on the one hand renders possible a quick clamping of the warps in the grips, and on the other hand a continuous, constant and complete supervision for the control of the tying of the warp, and of the warp threads already tied, a single completely free warp plane being obtained in the entire longitudinal direction of a plurality of machines coupled together, which facilitates the operation and supervision by the workers in an exceedingly advantageous manner.

23. What I claim is:—

23. 1. A machine for knotting a fresh warp to an existing warp, which warps are clamped and secured in grips, comprising carrying members which are constructed as downwardly bent bows, comprising bridge pieces passing through underneath the driving shaft, and the machine further comprising a toothed rack fixedly mounted upon the machine, a second toothed rack fixed to the warp carriage and displaceable with it, both of the said toothed racks being arranged inside the warp carriage in such a way that the transverse bridge pieces of the downwardly bent rows are continuous underneath the racks so that one and the same rack is made continuous for a plurality of machines coupled together, toothed wheels rotatably mounted on the knotting carriage and meshing with the said racks, ratchet wheels associated with the toothed wheels, and ratchet mechanisms for rotating the ratchet wheels and thereby displacing the knotting carriage and the warp carriage automatically and uninterruptedly.
40. 2. A machine for knotting a fresh warp to an existing warp lying opposite to it in a different horizontal plane in a plurality of machines coupled together, with clamped warps, comprising carrying members constructed as downwardly bent bows arranged below the planes of the warps, grips carried by the carrying members for receiving the fresh warp, the grips forming with the carrying members a travelling warp carriage, a driving shaft arranged in a longitudinal direction in the warp carriage between the grips, transverse bridge pieces forming part of the carrying members extending through underneath the driving shaft, a knotting carriage arranged in the warp carriage, rails

on the carrying members for the knotting carriage to travel on, knotting implements mounted on the knotting carriage in driving relationship with the driving shaft, means for automatically displacing the knotting carriage in a longitudinal direction from one machine to another for the tying of the previously prepared and clamped warps, a toothed rack fixedly mounted upon the machine, a second toothed rack fixed to the warp carriage and displaceable with it, both of the said toothed racks being arranged inside the warp carriage in such a way that the transverse bridge pieces of the downwardly bent bows are continuous underneath the racks so that one and the same rack is made continuous for a plurality of machines coupled together, toothed wheels rotatably mounted on the knotting carriage and meshing with the said racks, ratchet wheels associated with the toothed wheels, ratchet mechanisms for rotating the ratchet wheels and thereby displacing the knotting carriage and the warp carriage automatically and uninterruptedly, implements for throwing the knotting carriage out of operation, implements for taking away the threads from the warp, and means for actuating the knotting implements, all the actuating means for the knotting carriage disconnecting implements, the thread-removing implements, and the knotting implements, and the displacing means for the warp carriage and the knotting carriage, being located below the said implements and carriages and below the planes of the warps for rendering possible an unhampered quick clamping of the warps and a continuous and complete supervision of the warp when clamping and tying the same, also an easy control of the threads of the warps already knotted and over the entire longitudinal front even with a plurality of machines coupled together.

In testimony whereof I have affixed my signature.

ULRICH BISCHOF.
